KARL BARTH, OF ESSEN-ON-THE-RUHR, GERMANY, ASSIGNOR TO FRIED. KRUPP AKTIENGESELLSCHAFT, OF ESSEN-ON-THE-RUHR, GERMANY.

SELF-UNLOADING VESSEL.

1,188,608.

Specification of Letters Patent. Patented June 27, 1916.

Application filed October 20, 1913. Serial No. 796,272.

To all whom it may concern:

Be it known that I, KARL BARTH, residing at Essen-on-the-Ruhr, Germany, a subject of the Emperor of Germany, have invented 5 a certain new and useful Improvement in Self-Unloading Vessels, of which the following is a specification.

This invention relates to self-unloading vessels wherein the receptacle holding the 10 loaded goods is given rectangular cross section when in loading position, and which receptacle when transferred into discharging position changes its rectangular shape, so that even hard packed material will be automatically unloaded.

The subject matter of the invention resides in a self-unloading vessel of this kind, which is distinguished by a particularly simple construction and furthermore possesses the 20 advantage that the unloading may be made rapidly and conveniently.

One embodiment of the present invention is illustrated in the drawing representing a self-unloading car and Figure 1 shows a 25 cross section of the car in the loaded position and Fig. 2 a view similar to Fig. 1 of the car in unloading position.

The two end walls A¹ are rigidly secured on the bottom frame A of the car, and these 30 walls are reinforced at their corners by two rods a² and a³ parallel to the longitudinal axis of the car. The bottom B of the self-unloading car is, by means of a shaft b¹, revolubly mounted in bearings in the end 35 walls A¹, and this shaft is situated on the side of the car nearest to the rod a². The side wall C on this side of the car has a hinged connection with the bottom B and is at its upper end provided with rails c¹, 40 which are guided on suitable rollers a⁴ mounted on the rod a². The rails c¹ are bent at their upper ends, into hooks c², with which they engage the rollers a⁴ in the loading position of the car, see Fig. 1, so that 45 the bottom B is secured against turning in the direction of the arrow x. The opposite side wall C³ is hinged to the rod a³ and is provided with hooks c⁴ at its lower end, which hooks grip under the bottom B and 50 hold it in the loading position as illustrated in Fig. 1. In discharging position shown in Fig. 2, the bottom B rests on a beam a⁵ secured on the bottom frame A of the car. A crank connection with a hand lever D is 55 linked to the side wall C³, which is intended

either to lock the side wall in its loading position, or to swing it around its rod a³.

When the car is to be unloaded the hand lever D is turned in the direction of the arrow y, see Fig. 1, so that the side wall C³ 60 is swung outward and the hooks c⁴ disengage from the bottom B. As soon as this has taken place the weight of the loaded material will tip the bottom B in the opposite direction to that of the arrow x, in consequence of the shaft b¹ being situated to one side of the car, and this tipping of the bottom continues until the bottom is stopped by the beam a⁵. The side wall C, hinged to the bottom B, will as a consequence of this 70 movement be raised, while the rails c¹ are sliding on the rollers a⁴. The angle between the side wall and the bottom B will simultaneously grow larger, whereby the original rectangular shape of the car receptacle will 75 be changed. This condition makes it possible for packed material, such as clay, to be automatically unloaded, as on account of the change of the rectangular cross section of the car receptacle the adhesion, as 80 well as the cohesion of the loaded material will be considerably diminished. The automatic unloading will be still more augmented through the shaking of the material caused by the dropping of the bottom B 85 against the beam a⁵.

At the end of the discharge, the bottom B returns to its original loading position, Fig. 1, from its discharging position, Fig. 2, assisted by the weight of the side wall C 90 which is hinged to it, when the hooks c² re-engage the rollers a⁴, thereby preventing any continued movement of the bottom B. In order to secure the bottom B in this position the hand lever D of the crank connection has to be turned in the direction of the arrow z, see Fig. 2, until the side wall C³ 95 has arrived in the position shown in Fig. 1, when the hooks c⁴ engage under the body B.

I claim:

1. A self-unloading vessel comprising a frame, a receptacle of rectangular cross section when in loading position, said receptacle having two end walls rigidly mounted 105 on said frame, a bottom adapted to swing in its entirety about an axis parallel to the central longitudinal axis of the receptacle said axis lying between this longitudinal axis and one of the side walls of the recep- 110

tacle and hinged connection between this side wall and said bottom.

2. A self unloading vessel comprising a frame, a receptacle of rectangular cross section when in loading position, said receptacle having two end walls rigidly mounted on said frame, a bottom adapted to swing in its entirety about an axis parallel to the central longitudinal axis of the receptacle, 10 said axis lying between this longitudinal axis and one of the side walls of the receptacle, hinged connection between this side wall and said bottom, a rod on one side connecting the upper corners of said end walls, rollers on said connecting rod adapted to guide said side wall during the movement of said bottom, and a plurality of hooks at the upper end of said side wall adapted to engage the upper part of said rollers when the 20 receptacle is in the loading position.

3. A self unloading vessel comprising a rigid frame, and a receptacle of rectangular cross section when in loading position, said receptacle having two end walls rigidly 25 mounted on said frame, a rod on each side connecting the upper corners of said end walls, a pair of side walls suspended from said rods, one of said side walls mounted to swing on one of said connecting rods, a bottom, and a longitudinal shaft for said bottom carried in said end walls to one side of 30 the longitudinal axis of the bottom but away from its edge, said bottom being adapted to tilt in its entirety on said shaft.

35 4. A self-unloading vessel comprising a rigid frame, and a receptacle of rectangular cross section when in loading position, said receptacle having two end walls rigidly mounted on said frame, a rod on each side 40 connecting the upper corners of said end walls, a pair of side walls suspended from said rods, one of said side walls mounted to swing on one of said connecting rods, a bottom, and a longitudinal shaft for said bottom carried in said end walls to one side of 45 the longitudinal axis of the vessel, said bottom being adapted to tilt on said shaft, hooks at the lower end of the swinging side wall constructed to engage with and support 50 said bottom, and a longitudinal beam on said frame adapted to restrict the tilting of said bottom when the vessel is in unloading position.

55 5. A self-unloading vessel comprising a rigid frame, and a receptacle of rectangular cross section when in loading position, said receptacle having two end walls rigidly mounted on said frame, a rod on each side 60 connecting the upper corners of said end walls, a pair of side walls suspended from said rods, one of said side walls mounted to swing on one of said connecting rods, a bottom, and a longitudinal shaft for said bottom carried in said end walls to one side of 65 the longitudinal axis of the vessel, said bot-

tom being adapted to tilt on said shaft, hooks at the lower end of the swinging side walls constructed to engage with and support said bottom, and a longitudinal beam on said frame adapted to restrict the tilting of said bottom when the vessel is in unloading position, the other of said side walls, situated on the side nearest said shaft having hinged connection with said bottom, a plurality of hooks at the upper end of said second side wall, rollers on its connecting rod adapted to engage said hooks when the vessel is in the loading position and to guide said second side wall in its upward movement during the tilting of said bottom. 70 75 80

6. A self-unloading vessel comprising a rigid frame, and a receptacle of rectangular cross section when in loading position, said receptacle having two end walls rigidly mounted on said frame, a rod on each side 85 connecting the upper corners of said end walls mounted to swing on one of said connecting rods, a bottom, and a longitudinal shaft for said bottom carried in said end walls to one side of the longitudinal axis of the vessel, said bottom being adapted to tilt on said shaft, hooks at the lower end of the swinging side wall constructed to engage with and support said bottom, and a longitudinal beam on said frame adapted to restrict the tilting of said bottom when the vessel is in unloading position, the other of 90 said side walls, situated on the side nearest said shaft having hinged connection with said bottom, a plurality of hooks at the upper end of said second side wall, rollers on its connecting rod adapted to engage said hooks when the vessel is in the loading position and to guide said second side wall during the movement of said bottom, and 95 means for oscillating said swinging side wall. 100 105

7. A self-unloading vessel comprising a rigid frame, and a receptacle of rectangular cross section when in loading position, said receptacle having two end walls rigidly mounted on said frame, a rod on each side connecting the upper corners of said end walls, a pair of side walls suspended from said rods, one of said side walls mounted to swing on one of said connecting rods, a bottom, and a longitudinal shaft for said bottom carried in said end walls to one side of 110 the longitudinal axis of the vessel, said bottom being adapted to tilt on said shaft, hooks at the lower end of the swinging side wall constructed to engage with and support said bottom, and a longitudinal beam on said frame adapted to restrict the tilting of said bottom when the vessel is in unloading position, the other of said side walls situated on the side nearest said shaft having hinged connection with said bottom, a plurality of hooks at the upper end of said second side wall, rollers on its connecting rod 115 120 125 130

adapted to engage said hooks when the vessel is in the loading position and to guide said second side wall in its upward movement during the tilting of said bottom, and 5 means for oscillating said swinging side wall; said means comprising a crank handle journaled on one of the end walls and adjacent to said shaft, and a linked connection between said crank handle and said swinging wall.

8. A car having fixed end walls, a pivotally mounted bottom member, the pivotal axis of which is intermediate the sides of said bottom member, a side member pivotally mounted between the side end walls and 15

adapted to open outwardly from the car and to close inwardly and downwardly on the outer side of the bottom member, when the latter is in closed position, and a vertically movable wall pivotally connected to 20 the bottom member at the side opposite the said side member.

The foregoing specification signed at Bar-
men, Germany, this 30th day of September,
1913.
